United States Patent Office.

CHARLES WARD, OF DETROIT, MICHIGAN.

Letters Patent No. 94,260, dated August 31, 1869.

IMPROVED DEVICE FOR FILLING STEAM-GENERATORS.

The Schedule referred to in these Letters Patent and making part of the same.

To whom it may concern:

Be it known that I, CHARLES WARD, of Detroit, in the county of Wayne, and State of Michigan, have invented a new and useful Improvement in Apparatus for Filling Steam-Boilers; and I do declare that the following is a true and accurate description thereof, reference being had to the accompanying drawings, and to the letters of reference marked thereon, and being a part of this specification, in which—

Figure 1 is a perspective view of a boiler, with my device attached.

Figure 2 is a vertical section of the filler and check-valve.

Like letters indicate like parts in each figure.

The nature of this invention relates to a method of automatically refilling steam-generators when blown out, and consists in attaching to a boiler a pipe entering it at the water-line, the lower end of said pipe being provided with a check-valve, and terminating under the surface of the water whence the usual supply for the boiler is drawn, a vacuum being formed in the boiler by blowing it out, the pressure of the atmosphere causes the water to raise the check-valve, and rushing up the pipe, speedily fills the boiler.

In the drawings—

A represents an ordinary upright tubular boiler, provided with the usual blow-off cock B.

C is the filling-tube, tapped into the boiler at or above the water-line; this tube is carried down into the water whence the ordinary supply for the boiler is derived.

D is a check-valve, at its lower end closed by the pressure of the steam in the boiler.

After the boiler is blown out under pressure, the blow-off cock is closed, when a vacuum will be found to exist in the boiler, or will be formed by the rarefaction of the air contained in it, by the heat radiated from its plates. The pressure of the atmosphere upon the water causes it to raise the check-valve and fill the boiler to the point at which the pipe C enters it, thereby obviating the necessity of pumping to refill the boiler.

What I claim, and desire to secure by Letters Patent, is—

The arrangement of the pipe C, the check-valve D, and cock B, with the boiler A, substantially as described.
